UNITED STATES PATENT OFFICE.

GEORGE R. JENNINGS, OF BROOKLYN, NEW YORK.

WINDOW-SHADE FIXTURE.

SPECIFICATION forming part of Letters Patent No. 729,594, dated June 2, 1903.

Application filed January 20, 1903. Serial No. 139,769. (No model.)

To all whom it may concern:

Be it known that I, GEORGE R. JENNINGS, a citizen of the United States, residing at Brooklyn, in the county of Kings and State 5 of New York, have invented a new and useful Window-Shade Fixture, of which the following is a specification.

My invention relates to window-shade fixtures, and has for its objects to produce a simple and inexpensive mechanism which may be readily attached to the casing of any window for sustaining the shade-roller and permit the shade to be moved bodily up and down, thus admitting light and air either 15 above or below the shade and screening any desired portion of the window to exclude or soften the light.

To these ends the invention comprises the novel details of construction and combination of parts more fully hereinafter described and claimed.

In the accompanying drawings, Figure 1 is a front elevation of a window frame or casing having my device applied thereto. Fig. 2 is 25 a similar fragmentary view enlarged. Fig. 3 is a sectional view illustrating the stops at the upper and lower ends of the guideway. Figs. 4 and 5 are detailed views of the ends of the curtain-roller, illustrating my improved 30 means for preventing lateral displacement of the roller. Fig. 6 is a detailed perspective view of one of the brackets.

Referring to the drawings, 1 indicates a window-casing, which may be of the usual or 35 any desired construction, and 2 two vertical tracks or guides, secured to the casing by screws or otherwise. These tracks, which are mounted one at either side of the window, are preferably made from suitable sheet-metal 40 rolled or pressed into form to present two lateral flanges by means of which the track may be attached and a central web portion on which the curtain-sustaining brackets travel. Screwed or otherwise secured to the casing 45 over each of the tracks or guides is a sheave-carrying bracket 3, having horizontal feet which bear against the casing, and a vertical lug or extension 4, formed integral with the lower foot of the bracket and extending downward 50 therefrom into the hollow web of the upper end of the track or guide 2, by which construction the end of the guide will be se-

curely braced and strengthened to insure against accidental displacement of the same.

5 indicates a plate, preferably ornamental in character and in the form of a fleur-de-lis, screwed or otherwise suitably secured to the window-casing beneath the track or guide and provided with an integral lug or finger 6, which projects into the hollow web of the 60 guide at its lower end, thus securely bracing and strengthening the same to prevent its accidental displacement in a manner similar to that above described. This plate 5 also constitutes a stop for limiting the shade-roller-carrying bracket in its downward movement to prevent its escape from the track or guide.

7 indicates two brackets slidably mounted on the tracks or guides, one on each side of 70 the window-casing, which sustain the respective ends of the shade-roller and which in their travel up and down upon their guides move the roller and its shade bodily up and down in order to bring the shade to 75 any desired position for excluding or softening at any point the light which enters the window. These brackets, which are moved up and down upon the guides by suitable means to be hereinafter described, are identical in construction and operation. Hence but one of them will be described in detail. Each bracket is cast or otherwise formed from any suitable metal and is of substantially 80 U shape in side elevation and projects horizontally from the casing, with its arms 8 and 9 formed with suitable heads which [slidely] embrace the web of the track or guide. The heads on the arms are suitably grooved to permit the slideable engagement of the 85 heads with the guides and extend horizontally across the face of the guide and are each provided with a downwardly-depending portion which rests against the flanged extensions of the guide to prevent undue looseness or play 90 of the bracket. The outer end or bridge 10 of the bracket is provided with a suitable socket 10^a, formed by an upwardly-projecting integral finger 11, formed on the bracket, said socket being adapted to receive a bearing-pin 12, which projects from the end of the curtain-roller 13, as usual, while the opposite end of the roller is provided with a 100 similarly-projecting end 14, having a head

15 formed at its outer end and adapted to engage the bracket to prevent lateral displacement of the roller. The bearing-pin 12, which is angular in cross-section, has a suitable metal thimble applied thereto and carrying a head 16, which prevents lateral displacement of the roller in the opposite direction. In this connection it is to be noted that the thimble will frictionally engage the pin with sufficient security to prevent detachment of the thimble during ordinary usage of the device.

17 indicates a suitable cord or the like secured at one end to a screw-eye or other similar fastening 18 at the bottom of the window-casing and passed upward and around the sheaves or rollers at the top of the casing, with its other end attached to the far shade-supporting bracket, while a second cord is attached at one end to the near shade-supporting bracket and has its opposite end attached to a plate or member slidably mounted on the cord 17, by which means the brackets will be simultaneously moved upward by a downward pull on the cord and will when the cord 25 is slackened fall uniformly by gravity, thus moving the shade-roller bodily up and down for the purpose above specified. The bracket-operating cords are each attached to its respective bracket by passing its end through a suitable orifice formed in the bridge portion 30 of the bracket just at the upper or open end of the socket 10^a and knotting the same, by which construction the knot will constitute a stop to prevent the accidental escape 35 of the bearing-pin from its socket.

19 indicates a cleat stamped from a single piece of metal and screwed to the window-casing in position to receive the cord by which

the brackets are operated to hold the latter in their various positions.

20 is a plate, preferably ornamental in nature, which lies beneath the cleat and is secured in place by the screw which holds the latter. This plate, which may contain the name of the company or other desired working, serves as a shield to prevent soiling or in any manner marring the woodwork of the casing when cleating the cord.

Having thus described the invention, what I claim is—

1. In a window-shade fixture, the combination with a shade-roller, of end brackets therefor provided with sockets, bearing-pins projecting from the ends of the roller and mounted in the sockets, and means including a cord 55 for moving the brackets up and down, said cord having its end passed through an orifice formed in the bracket and knotted at the open end of the socket, whereby the knot will constitute a stop to prevent accidental escape of 60 the bearing-pin from the socket.

2. In a window-shade fixture, the combination with a shade-roller, of bearing-pins projecting therefrom, end brackets provided with sockets adapted to receive the bearing-pins, 65 and a metal thimble mounted upon one of the pins and provided with a head to prevent lateral displacement of the roller.

In testimony that I claim the foregoing as my own I have hereto affixed my signature in 70 the presence of two witnesses.

GEORGE R. JENNINGS.
